UNITED STATES PATENT OFFICE.

CHARLES D. BONSALL, OF PARNASSUS, PENNSYLVANIA, ASSIGNEE TO WALTER P. MURPHY, OF NEW YORK, N. Y.

RAILWAY-CAR-WALL CONSTRUCTION.

1,374,421.

Specification of Letters Patent. Patented Apr. 12, 1921.

Original application filed November 14, 1919, Serial No. 338,075. Divided and this application filed August 21, 1920, Serial No. 405,017.

To all whom it may concern:

Be it known that I, CHARLES D. BONSALL, a citizen of the United States, residing at Parnassus, in the county of Westmoreland and State of Pennsylvania, have invented certain new and useful Improvements in Railway-Car-Wall Constructions, of which the following is a specification.

My invention relates to reinforced car end structures and has for one of its objects to provide a novel and improved sheet metal structure, particularly for the end walls of a railway box car, which will be strong and rigid.

15 A further object is to provide an end wall construction made up of a plurality of sheets having reinforcing ribs formed therein, the size of the sheet and form of the ribs being so proportioned as to permit the same 20 to be pressed in smaller presses having a more limited power than those for pressing larger sheets having the ordinary form of reinforcing ribs.

25 A further object is to provide an improved construction for anchoring or attaching the ends of the reinforcing ribs to the corners of the car so as to increase the strength and rigidity of the end structure.

The invention consists in the novel constructions, arrangements, and combinations to be hereinafter described and claimed for carrying out the above stated objects and such other objects as will appear from the following description.

35 The invention is illustrated in a preferred embodiment in the accompanying drawings, wherein:

Figure 1 is an elevation of a car end wall constructed of metal sheets embodying the 40 principles of my invention.

Fig. 2 is a cross section of the end structure shown in Fig. 1 taken on the line 2—2 of Fig. 1.

Fig. 3 is a fragmentary perspective of a 45 single sheet or panel used in the construction of the wall.

Fig. 4 is a vertical section taken along the line 4—4 of Fig. 1.

Fig. 5 is a central vertical section taken 50 along the line 5—5 of Fig. 1.

Like characters of reference designate like parts in the several figures of the drawing.

For the purpose of illustration I have shown my invention as applied to a box car

of ordinary construction. It is obvious that 55 the invention may be employed in connection with other types of railway cars, such as gondola cars.

The car as shown is provided with the usual roof construction 12, and side walls 60 13. The end wall structure 14 of the car is made up of a plurality of relatively narrow sheets 15 of the same general construction but preferably differing in width with the narrower sheets at the bottom so as to increase the number of stiffening ribs at the lower part of the car as shown in Fig. 1. The upper and lower sheets 16 and 17, respectively, are of special construction so as to provide for connection with the roof and 70 end sill, respectively.

Each sheet 15 and sheet 16 is formed with a reinforcing or rigidifying rib 18 which has its maximum depth at the middle and decreases in depth toward the sides of the 75 sheet. The rib is in the form of an angle bar at the middle as shown in Fig. 5, but of hollow or channel shaped construction near its ends as shown at 19 (see Fig. 4). The channeled portions are formed by bending down the corners of the plates along diagonal lines corresponding substantially to the taper resulting from the decrease in depth of the rib toward its ends. The bent over sides 20 of the channeled portions 19 80 are further bent to form flanges 21 adapted to be riveted to the adjacent plate. The ends of the rib 18 merge into the plate at or near vertical ends which form attaching flanges 22.

The lower portion of each plate 15 is offset along a line indicated at 23, adjacent the rib 18 where it overlaps the plate below so the interior of the wall structure has a substantially flat surface.

If desired the end wall structure may be provided with an end lining consisting of lining boards 24 nailed or otherwise secured to a suitable number of vertical, spaced, nail-ing strips 25, which are bolted or otherwise secured to the end wall.

The rigidifying rib 18 is so proportioned that the same may be formed in a press of limited power inasmuch as there is very little "draw" of the metal in pressing the plate, the rib being formed chiefly of bending which requires less power than drawing. By providing the attaching flanges 22

adjacent the ends of the reinforcing ribs, the ribs may be anchored to the corner posts 26 or to the side of the car so as to constitute in effect beams having fixed ends. This increases the rigidity of the structure inasmuch as a beam anchored or fixed at its ends is more rigid than one not so anchored.

The width of the sheets 15 may be varied to provide as many reinforcing ribs in a 10 certain region of the structure as are necessary to adequately strengthen the end and to resist weaving and other strains.

This application is a division of my co-pending application Serial No. 338,075 filed 15 November 14, 1919.

I claim:

1. A sheet metal end panel for a railway car comprising a metal sheet formed with a pressed rigidifying rib having an angle bar 20 configuration at the middle and its ends bent over on diagonal lines to provide channeled portions which taper in depth and which terminate with closed ends adjacent the sides of the car.
2. A sheet metal end panel for a railway car comprising a metal sheet formed with a pressed rigidifying rib having an angle bar configuration for a portion of its length the rest being channeled, said panel provided with flanges at the ends thereof extending beyond the extremities of the rib for anchoring the ends of the panel to the car.
3. A sheet metal end panel for a railway car comprising a metal sheet formed with an outpressed rigidifying rib having its greatest depth adjacent its middle and diminishing in depth toward its end and which has an angle bar configuration at the middle 40 and is channel formed at its ends, said ends being provided with anchoring flanges adapted to be attached to the sides of the car and the extremities of the channels being closed.
4. In a sheet metal end for a railway car, a metal sheet formed with side attaching flanges extending the entire height of the sheet and adapted to be secured to the side of the car and also formed with an out- 50 pressed rigidifying rib adjacent one edge, said rib diminishing in depth toward its ends, of angle bar configuration at the middle and in the form of channels at its extremities with the ends of the channels 55 closed.
5. In a sheet metal end for a railway car, a metal sheet formed with a rigidifying rib, the ends of which merge into the sheet and the sheet being provided with attaching 60 flanges, said rib being hollow adjacent its ends and of angle bar configuration at the middle and increasing in depth toward the middle of the sheet.
6. In a sheet metal end for a railway car, 65 a metal sheet having one of its horizontal

marginal portions pressed outwardly to form an angular rigidifying rib diminishing in depth toward the ends thereof, the corners of said sheet being bent over to provide channel shaped portions at the ends of said 70 ribs which merge into the sheet near the side edges thereof.

7. A sheet metal end structure for railway cars comprising a plurality of horizontally disposed sheets, the lower edges of 75 which overlap the upper edges of the adjacent sheets and are formed with outpressed rigidifying ribs which are of angular bar configuration and of greatest depth at the middle and terminate in channel shaped 80 tapering portions that merge into the sheet adjacent the sides of the car.

8. A sheet metal end structure for railway cars comprising a plurality of horizontally disposed sheets, the lower edges of 85 which overlap the upper edges of the adjacent sheets and are formed with outpressed rigidifying ribs which are of angle bar configuration and of greatest depth at the middle and terminate in channeled tapering 90 portions that merge into the sheet adjacent the sides of the car, the sheets being provided with attaching flanges at the ends thereof.

9. In a sheet metal end for a railway car, 95 a metal sheet having a margin thereof bent outwardly to form an angular rigidifying rib and having the corner portions of said margin bent to form channeled portions constituting prolongations of the angular 100 portions of said ribs, the extremities of said corners constituting attaching flanges, and side flanges on said sheet opposite the ends of said rib for anchoring the ends thereof to the car.

10. A sheet metal structure for a railway car, comprising a plurality of sheets the horizontal margins of which overlap adjacent sheets, each sheet being formed along one of said margins with an outwardly 110 pressed angular rigidifying rib, the corner portions of said margin being bent over along a diagonal line to form channeled portions diminishing in depth toward the ends, the extremities of said corner portions extending from said channeled portions and constituting flanges adapted to be attached to the adjacent sheets, and side flanges on 115 said sheets opposite the ends of said rib for anchoring the ends thereof to the car. 120

11. A sheet metal end structure for railway cars comprising a plurality of metal sheets overlapped and secured together and formed along said overlapped portions with reinforcing ribs, the ends of which are channel-formed and closed at their extremities, and the middle portions in the form of webs having free edges standing away from the sheets.

12. A sheet metal end structure for rail- 130

way cars comprising a plurality of metal sheets overlapped and secured together, one of the overlapped marginal edge portions of each sheet being pressed away from the 5 plane of the sheets to provide a projecting rib, the ends of which are pressed toward the plane of the sheets to provide channel-formed portions which merge at their 10 extremities into the sheet and are secured along their edges to an adjacent sheet.

13. A sheet metal end structure for railway cars comprising a plurality of metal sheets overlapping and secured together, one of the overlapped marginal edge portions of each sheet being pressed away from the 15 plane of the sheets to provide a projecting rib, the edge of which at the middle is free from the adjacent sheet and the ends

of which are bent toward the plane of the sheets to provide channel forming portions 20 which merge at their extremities into said sheets, respectively, and are secured at their edges to an adjacent sheet.

14. A sheet metal end structure for railway cars comprising a plurality of metal sheets arranged one above the other, overlapped and secured together, the lower edges 25 of the sheets being pressed away from the plane of the sheets to provide projecting ribs having free edges at the middle standing 30 away from the sheets and end portions pressed toward the sheets which at their extremities merge into said sheets, respectively, and are secured along their edges to adjacent sheets, respectively.

CHARLES D. BONSALL.
